UNITED STATES PATENT OFFICE.

FRANCIS A. STROUGH, OF PHILADELPHIA, NEW YORK.

DESIGN FOR A BADGE.

SPECIFICATION forming part of Design No. 21,230, dated December 8, 1891.

Application filed December 13, 1890. Serial No. 374,651. Term of patent 14 years.

To all whom it may concern:

Be it known that I, FRANCIS A. STROUGH, a citizen of the United States, residing at Philadelphia, in the county of Jefferson and State 5 of New York, have invented and produced a new and original Design for a Badge, Button, or Pin, of which the following is a specification, reference being had to the accompanying photograph, forming a part thereof.

10 The photograph illustrates a face view of my design, and is deemed sufficient to fully illustrate the same.

The leading feature of the design consists of a background having a circular outline 15 and configured surface, a panel on said background formed by intersecting lines, a second panel upon said surface, and a bar or band at the lower part of the background having a rounding outer face.

20 A represents the background of my design, which is formed with a circular outline *a* and a configured surface *a'* for representing a portion of the continents of the globe.

B represents a panel formed by intersect- 25 ing lines *b b* for representing a cross.

C represents a panel upon the raised panel B at the point of intersection of the cross or

panel B, being formed of parallel sides *c*, and the sides *c'* having their opposite extremities inclining one from the other for representing 30 a Bible open at John III, xvi.

D represents a bar or band upon the back- 35 ground A, having a rounding outer surface, which is formed with a series of elevations and depressions for representing a pair of clasped hands. This particular arrangement of background and panels forms a very desirable, pleasing, and attractive arrangement, which renders the badge, button, or pin very desirable, ornamental, and salable. 40

Having thus fully described my invention, what I claim as new, and desire to secure by Letters Patent, is—

The design for a badge, pin, or button, substantially as herein shown and described. 45

In testimony whereof I have hereunto signed my name, in the presence of two attesting witnesses, at Philadelphia, in the county of Jefferson, in the State of New York, this 9th day of December, 1890.

FRANCIS A. STROUGH.
